Primary Examiner — Sandra Snapp*Assistant Examiner* — Ieisha Price(74) *Attorney, Agent, or Firm* — Fitch, Even, Tabin & Flannery LLP(57) **CLAIM**

I claim the ornamental design for a clip for securing string or rope, as shown and described.

DESCRIPTION

FIG. 1 is a front perspective view of a clip for securing string or rope;

FIG. 2 is a rear perspective view of the clip for securing string or rope of FIG. 1;

FIG. 3 is a rear view of the clip for securing string or rope of FIG. 1;

FIG. 4 is a front view of the clip for securing string or rope of FIG. 1;

FIG. 5 is a right side view of the clip for securing string or rope of FIG. 1;

FIG. 6 is a left side view of the clip for securing string or rope of FIG. 1;

FIG. 7 is a top plan view of the clip for securing string or rope of FIG. 1; and,

FIG. 8 is a bottom plan view of the clip for securing string or rope of FIG. 1.
